UNITED STATES PATENT OFFICE.

ALBERT EDWARD HORNBY, OF RHYL, WALES.

FLUSHING APPARATUS FOR WATER-CLOSETS AND THE LIKE.

1,304,482.

Specification of Letters Patent.

Patented May 20, 1919.

Application filed July 8, 1918, Serial No. 243,926.

To all whom it may concern:

Be it known that I, ALBERT EDWARD HORNBY, a subject of the King of England, residing at Rhyl, North Wales, Great Britain, 5 have invented certain new and useful Improvements in and Relating to Flushing Apparatus for Water-Closets and the like, of which the following is a specification.

My invention relates to flushing apparatus 10 for water closets and the like, and to the type of apparatus in which a closed-in vessel or reservoir, capable of being sealed, receives the flushing water, said closed-in vessel being provided at the top with a float 15 valve which opens to air when emptying and is closed by the incoming water when the same reaches the top or thereabout of the vessel, compressing the air therein, so that on the flushing valve being opened the 20 first flow of water takes place under compressed air till the seal of the vessel is broken by the float valve opening to atmosphere after which the flush is by gravity.

The present invention has for its object 25 the improved combination, construction, arrangement and working parts constituting the apparatus as herein described and shown in the drawings. In the latter:—

Figure 1 is an elevation, partly in section, 30 of the apparatus;

Fig. 2 is a plan view, partly in section, and drawn to a larger scale, of the flushing valve and operating means therefor;

Fig. 3 is a sectional elevation, drawn to a 35 larger scale, of the air chamber of the apparatus;

Fig. 4 is an end view, also drawn to a larger scale, of the means for actuating the water supply tap; and

Fig. 5 shows some details, partly in section.

Similar parts are designated by like references throughout the several views.

In carrying out my invention I make provision of a closed-in vessel or cistern *a* with water connections *i*, *i* at its lower end, Fig. 1, and to one of these connections *i*—the other being capped—is attached the branch pipe *c*¹, Fig. 4, leading from the water supply tap *c*². To the top of the cistern *a* there is attached an air-chamber *b*, Figs. 1 and 3, the same having therein a float valve *j* and valve seating *j*¹, and *c* is the air inlet pipe to said chamber *b*.

To the upwardly dished bottom *k* of the cistern *a* there is connected the flushing

chamber or valve *b*¹ which is divided into two parts by a partition *h* in which is formed the valve seating *h*¹. The valve disk *d* and integral valve, shown in Fig. 1 in closed position and in Fig. 2 in open position, are carried by a valve rod or spindle *d*¹ which passes through a stuffing box and regulating nut *g* arranged in the flushing chamber *b*¹. The spindle *d*¹ is provided 65 with a forked and slotted outer guide end *d*², and above said slots passes the pivot pin *f*¹ of the actuating handle *f*, the ends of said pivot pin *f*¹ being adapted to take in the ends of the extensions or brackets *b*² forming 70 integral parts of a nut or casing *x* which is screwed onto a branch *y* of the flushing chamber *b*¹, Fig. 2. The handle *f* is moreover provided with a chain *l* by means of which it can be pulled down when in the position indicated in Figs. 2 and 4. *e* is a coiled spring encircling the valve rod or spindle *d*¹, one end of said spring bearing against the nut *g* and the other end against the forked end *d*² of the spindle. The compression of the spring *e* can thus be regulated by means of the nut *g*.

On one of the laterally projecting ends of the pivot pin *f*¹ is mounted a counter balancing weight *a*¹, Figs. 2 and 4, in such a 85 manner as to tend to keep the handle *f* normally in an upright position and thereby holding the valve *d* open. The handle—in relation to its upright position—is formed at its lower end with an integral extension 90 in the shape of a forked boss adapted to receive a roller *f*² so that upon the handle being pulled down the roller *f*² is brought to bear against the inner end of the forked member of the spindle *d*¹ thereby compressing 95 the spring *e* and closing the valve *d* to close, Fig. 1.

On the other projecting end of the pin *f*¹ is slidably mounted a socket piece *e*² which normally is in engagement with the plug *g*¹ 100 of the water supply tap *c*², but, when required, can be disengaged from said plug as shown in Fig. 4.

In action, water from the town's supply, constant and under pressure, enters the cistern *a* by way of the tap *c*², branch *c*¹, and union or connection *i*, rising in the cistern, driving out the air therein, which air passes the float valve *j* in the chamber *b*, Fig. 3, and escapes by way of pipe *c*. On the water 105 reaching said float valve *j*, the latter is lifted on to its seating *j*¹, sealing, and maintaining

sealed by the constant pressure of water, the vessel or cistern *a*.

When a flush is required, the handle *f* is pulled down which movement causes a corresponding rotary movement of the pivot pin *f*¹ and the socket piece *e*² which in turn, actuates the plug *g*¹ of the tap *c*² thereby opening the water supply and permitting a certain quantity or charge of the cistern, say 10 three gallons, being used at the time of flushing.

This downward movement of the handle *f* also brings into action the roller *f*² and causes the shutting of the valve *d* in the 15 manner hereinbefore described, the downward movement being arrested by pins or rollers *e*¹ suitably mounted in the extensions of the bracket *b*² and the slotted portion of the fork *d*² respectively. Upon the release 20 of the handle *f* the latter, by the action of the counter balancing weight *a*¹ and the spring *e*, returns to its normal position, Figs. 2 and 4, the valve *d* thus being withdrawn from its conical seat *h*¹ and allowing 25 the water to flow through the flushing chamber *b*¹ and outlet pipe *b*³ in order finally to pass to the pan or the like to be flushed.

At the same time the seal of the chamber *b* is broken, the float disk *j* dropping from off 30 its seat *j*¹ in said chamber, thus permitting of the ingress of air to the vessel or cistern *a*. Whenever a flush is required, the same process is repeated; that is, the handle *f* is pulled down and, after a certain time, released. 35

In order to prevent corrosion or foreign matter to pass into the cistern *a*, I prefer to employ a perforated zinc screen or filter *K*, Fig. 5, the said filter being mounted in a 40 three-way branch pipe of which the branch *L* is connected with the inlet tap *c*², while the branch *L*¹ is designed to be connected to the town supply pipe. The third branch *M* is ordinarily closed by means of a screw 45 plug *N* adapted to be disconnected to permit the filter to be taken out for cleaning purposes.

Having now fully described my said invention what I claim and desire to secure by 50 Letters Patent is:—

1. In the herein described flushing appa-

ratus, the combination, with a cistern and water inlet and air outlet connections provided thereon, of a two-part flushing chamber arranged at the bottom of the said cistern and communicating with same, a bracket casing attached to the flushing chamber and having slotted extensions, a 55 slideable and spring-controlled valve spindle mounted within the bracket casing, a disk valve secured to the inner end of said spindle and projecting into the flushing chamber and opposite a conical valve seat provided in the partition of said chamber, means to regulate the compression of the spring of 60 the valve spindle, and means to control in unison the water inlet and the flushing valve, all substantially as set forth and for the purpose shown.

2. In the herein described flushing apparatus, the combination, with a cistern and water inlet and air outlet connections, of a two-part flushing chamber arranged at the bottom of the cistern and communicating with same, a conical valve seat formed in 70 the partition wall of said chamber, a bracket attached to the latter and having slotted extensions, a slideable spring-controlled valve spindle mounted within the body of the said bracket, a disk valve secured to the inner 75 end of the spindle, and means to simultaneously actuate the valve and the water supply, said means comprising a forked extension provided at the outer end of the valve spindle, a handle pivotally mounted in the 80 extensions of the aforesaid bracket and having a downwardly projecting boss, a roller journaled therein and adapted to be brought to bear against the forked extension of the 85 valve spindle, and a pin forming the pivot 90 of the handle, one end of said pin carrying a counter balancing weight and the other end connecting with and operating the tap of the water supply, all as and for the purpose set forth.

In testimony whereof I have hereunto set my hand in the presence of two subscribing witnesses.

ALBERT EDWARD HORNBY.
